McCullough v Smith,
School Desk.
NO. 4206. Patented July 5, 1870.

Fig. 1.

Fig. 2.

Witnesses

G. F. Glazier
Abdul G. Bils

INVENTOR
J. H. McCullough
and
F. W. Smith
per Edward F. Smith
Attorneys

United States Patent Office.

ES K. McCULLOUGH AND FRANK W. SMITH, OF BURLINGTON, IOWA.

Design No. 4,206, dated July 5, 1870.

DESIGN FOR A BRACE FOR SCHOOL DESKS.

The Schedule referred to in these Letters Patent and making part of the same.

whom it may concern:

t known that we, JAMES K. McCULLOUGH and x W. SMITH, of Burlington, in the county of loines and State of Iowa, have invented and ed a new and original Design for an Improved for School Desk; and we do hereby declare that llowing is a full, clear, and exact description f, reference being had to the accompanying
g and to the letters of reference marked thereon.

Drawing.

ire 1 is a rear elevation of a desk, showing our ed brace attached thereto, and ire 2 is a side elevation.

ilar letters of reference denote like parts in both figures.

he annexed drawing forming a part of this speci-
on—epresents a circular bar secured to the back of it immediately under the top, its ends projectwnward, crossing the bars B and C, and secured end supports of the desk.

a circular bar, which has a position the exact e of the bar A; it is secured to the seat and s shown, its ends projecting upward, crossing eight bars C C, and circular bar A, joining the C at their ends, and they together secured to d supports of the desk.

C C are cross or straight bars, which have their point of contact within the oval space formed by the circular bars A and B, their upper ends being secured to the desk with the ends of the bar B, as before described; the lower ends of said cross-bars being secured to the said supports of the desk at a point below the seat of the desk.

These bars have lugs or lips, a a, at their ends,
through which the bolts, screws, and the like, pass,
which secure them to the desk.

With our improved brace a neat, durable, and economical desk is obtained.

Claim.

We claim as our invention—

The design of a brace for a school desk, as herein described and shown, with any and all parts thereof.

In testimony whereof we have signed our names to this specification at Burlington, in the county of Des Moines and State of Iowa, this 13th day of June, 1870.

J. K. McCULLOUGH.
F. W. SMITH.

Witnesses:

T. J. TRULOCK,
E. P. SUNDERLAND.